US00D643976S

(12) **United States Design Patent**
Wonderley et al.

(10) **Patent No.:** **US D643,976 S**
(45) **Date of Patent:** ** *Aug. 23, 2011

(54) **RAZOR CARTRIDGE**

(75) Inventors: **Jeffrey W. Wonderley**, Fort Defiance, VA (US); **Frank Prochaska**, Waynesboro, VA (US)

(73) Assignee: **American Safety Razor**, Verona, VA (US)

(*) Notice: This patent is subject to a terminal disclaimer.

(**) Term: **14 Years**

(21) Appl. No.: **29/377,235**

(22) Filed: **Oct. 19, 2010**

(51) **LOC (9) Cl.** **28-03**

(52) **U.S. Cl.** **D28/47**

(57) **CLAIM**

The ornamental design for a razor cartridge, as shown and described.

DESCRIPTION

FIG. 1 is a front perspective view of the razor cartridge, showing the new design;

FIG. 2 is a front view of the razor cartridge;

FIG. 3 is a rear view of the razor cartridge;

FIG. 4 is a side view of the razor cartridge;

FIG. 5 is another side view of the razor cartridge;

FIG. 6 is a bottom view of the razor cartridge; and,

FIG. 7 is a top view of the razor cartridge.

The broken lines showing various elements of the razor cartridge are included for the purpose of illustrating non-claimed subject matter and form no part of the claimed design.

1 Claim, 5 Drawing Sheets
